UNITED STATES PATENT OFFICE.

JOSEPH WILLARD GAMBLE, OF PHILADELPHIA, PENNSYLVANIA.

FEED-WATER HEATER AND PURIFIER.

No. 926,109.

Specification of Letters Patent.

Patented June 29, 1909.

Application filed July 6, 1908. Serial No. 442,943.

To all whom it may concern:

Be it known that I, JOSEPH WILLARD GAMBLE, a citizen of the United States, a resident of and whose post-office address is 5 No. 3251 North Sixteenth street, in the city of Philadelphia, county of Philadelphia, and State of Pennsylvania, have invented certain new and useful Improvements in Feed-Water Heaters and Purifiers, of which the following is, taken in connection with the accompanying drawings, a concise and complete description thereof.

My invention comprehends specifically the combination of one or more feed water heaters with an extension or storage tank and pressure regulating means intermediate the same for taking the strain due to the pressure created within the feed water heater from the storage tank, or preventing such pressure from being exerted on the tank.

Referring to the accompanying drawings, in which like numerals indicate like parts throughout, Figure 1 represents a heater and extension or storage tank, in side elevation, 25 equipped with one form of my invention. Fig. 2 is a top plan view showing a plurality of heaters with a common storage tank.

Referring in detail to the drawings, —1— indicates a feed water heater of the well known open type in which the supplied raw water is brought into physical contact with the supply of exhaust steam.

2— indicates a separator, and 3— an exhaust steam inlet.

35 4— indicates a dividing box which distributes to the heater units (where a plurality are used) a proper and uniform supply of the raw water.

5— indicates a raw water supply pipe connection having therein a float actuated valve —6— which is controlled by a float within the float chamber —7— by and through intermediate mechanism —6'.

9— indicates a suitable vent pipe, and 45 —10— an overflow for the extension tank.

Connecting the feed water heater —1— with the extension tank —8—, I provide a pipe connection —11— which is water sealed. This water seal connection comprises a perpendicular pipe, which is dipped or reversed upon itself, one end connected with the feed water heater, and the other end connected with the extension tank as shown. The length of the water seal connection is proportionate to the amount of pressure carried 55 within the heater units.

12— indicates a gate valve in the leg, connected with the extension tank, which is adapted to shut off the communication therewith. 60

13— indicates a pipe connection connecting one of the heater units with the water sealed pipe connection —11— at —14—.

15— indicates the outlet from the extension tank, said outlet being controlled by a suitable gate valve —16—. The outlet pipe —15— is connected with a pipe —17— which conveys the treated water to feed pumps or other points of use. 65

An auxiliary outlet —11'— to the water sealed pipe connection —11— is provided, which connects it with the feed water pipe —17—, and is for the purpose of directly feeding the water from the heating unit to feed pumps or other points of use when it is 70 desired to utilize the water without passing it into and drawing it from the storage tank. A valve, —11"— is provided in feed pipe —17— to control the passage of the water from the pipe connection —11— there. 80

By employing the water sealed connection —11— I am able to construct the extension or storage tank of much lighter material than the heater units themselves, as the strain that would be created by reason of the pressure carried within the heater units is thus relieved or taken off the storage tank. 85

Where I have used the word "separate" I do not necessarily mean that the storage 90 tank is away or apart from the heater. On the contrary, the same may be separate, but yet in physical contact with one another.

While I have shown a single extension or 95 storage tank connected to a heating unit or a plurality of heating units, I would have it understood that I am not limited in this respect, as it is manifest that a plurality of extension or storage tanks operating in connection with a plurality of heating units 100 may be employed, without departing from the spirit and scope of my invention.

I would further have it understood that I am not limited to the particular arrangement, size, design, or construction of the 105 apparatus constituting my invention as described, as the same may be altered or changed, and still come within the scope and tenor of my claims.

Having thus described my invention, what 110 I claim as new herein and desire to protect by Letters Patent, is:

1. The combination of a water heater and tank; an exterior passage between the same; and a pressure regulating means in said passage intermediate the heater and tank.
- 5 2. The combination of a water heater and a tank; a water sealed conduit exterior of and intermediate and connecting the same.
3. The combination of a water heater and a tank; an exterior passage dipped and re-
10 ersed upon itself intermediate and connect-
ing the same, and means therein for regu-
lating the flow therethrough.
4. The combination of a water heater and a tank an extension U shaped; water sealed
15 passage intermediate and connecting the same, and means for regulating the flow therethrough.
5. The combination of a plurality of heating units; a tank; and an intermediate ex-
20 teriorly arranged passage connecting said heating units and tank; and means comprising a dipped water sealed pipe operating to prevent the transmission of strain or pressure from the heater to the tank.
- 25 6. The combination of a plurality of heating units; a tank and an intermediate exterior passage connecting said heating units and tank; and means operating to take ex-
cessive strain or pressure off the extension
30 tank.
7. The combination of a plurality of heat-
ing units; a float controlled raw water sup-
ply; means for effecting the equal distribu-
tion of said raw water supply to said units
a storage tank; an exhaust steam supply for
35 each of said heater units; and pressure regu-
lating means intermediate the said heater
units and said tank.
8. The combination of a heating unit; a storage tank an outlet therefor, a water sealed passageway intermediate and connecting said heating unit with said storage tank and an auxiliary outlet from said water sealed passageway connecting with said outlet to said storage tank.
40
9. The combination of a plurality of heating units; a raw water supply and a steam supply, a distributing box for effecting an equal distribution of raw water to each of the heating units; a storage receptacle and
45 a water sealed passage, intermediate and connecting the heating units with said storage tank.
10. The combination of a heating unit; a tank; and an intermediate exterior passage connecting said heating unit and tank, and means operating to take excessive strain or pressure off the extension tank.
50

JOSEPH WILLARD GAMBLE.

In presence of—

JOSEPH M. HEWLETT,
D. J. HUNTER, Jr.
